UNITED STATES PATENT OFFICE.

STANLEY B. O'KANE, OF ELMHURST, NEW YORK, ASSIGNOR TO HUBERT J. BRAUN, OF CHICAGO, ILLINOIS.

DESIGN FOR A LIGHTING-FIXTURE HUSK OR SIMILAR ARTICLE.

Application filed November 3, 1924. Serial No. 11,274. Term of patent 7 years.

To all whom it may concern:

Be it known that I, STANLEY B. O'KANE, a citizen of the United States, and a resident of Elmhurst, county of Queens, and State of New York, have invented a new, original, and ornamental Design for Lighting-Fixture Husks or Similar Articles, of which the following is a specification, reference being had to the accompanying drawing, forming a part hereof.

In these drawings:

Fig. 1 shows an inverted plan view of the lighting fixture husk or similar article, the portion indicated in full line outline in the drawing being ornamented in the same manner as the portion more fully illustrated.

Fig. 2 shows a side elevation of the lighting fixture husk or similar article, the portion indicated in full line outline in the drawing being ornamented in the same manner as the portion more fully illustrated.

I claim:

The ornamental design for a lighting fixture husk or similar article substantially as shown and described.

STANLEY B. O'KANE.
